COMBINED CUTTING AND DRILLING RIGHT ANGLE DRIVE AND SUPPORT FOR POWER TOOLS

Bobby L. Terry, 843 Zachry Drive, San Antonio, Tex.

Filed Mar. 7, 1962, Ser. No. 69,117

Term of patent 14 years

(Cl. D54—4)

FIG. 1 is a side elevation view of the combined cutting and drilling right angle drive and support for power tools of this invention;

FIG. 2 is a rear end view of FIG. 1;

FIG. 3 is a front end view of FIG. 1;

FIG. 4 is a top plan view of FIG. 1; and

FIG. 5 is a bottom plan view of FIG. 1.

I claim:

The ornamental design for a combined cutting and drilling right angle drive and support for power tools, substantially as shown.
